MACHINES FOR APPLYING PRESSURE TO SHOE BOTTOMS

Lawrence Mawbey, Leicester, England, assignor to United Shoe Machinery Corporation, Flemington, N. J., a corporation of New Jersey

Application March 7, 1952, Serial No. 275,426

Claims priority, application Great Britain March 27, 1951

7 Claims. (Cl. 12—33)

This invention relates to machines for applying pressure to shoe bottoms and particularly to single presses for use in cement-attaching soles to shoes.

Objects of the invention are to provide a single machine as distinguished from a double or twin machine whereby soles may be attached to shoes with pressure-responsive cement and whereby the production of such shoes may be increased.

Modern cements containing synthetic rubbers, when applied to a lasted shoe and its sole and allowed to dry for a period, become pressure responsive; that is, when sufficient pressure is applied, even for a moment, between the shoe and sole they adhere firmly to each other. Such cements, if allowed to dry too long on the shoe and sole, may be treated with heat or a solvent to restore the pressure-responsive condition of the cement. Moreover, soles of synthetic rubber or crepe may be attached with these cements very readily since, under pressure, they conform to the shape of the shoe bottom more easily than leather. The illustrated machine comprises a column carrying a transversely extending pad box at a convenient height for an operator and an electric motor to provide power for raising the pad box. Abutments above the shoe and sole placed on the pad engage one the last and the other the forepart of the shoe. The abutments are adjustable longitudinally of the shoe and have step adjustments heightwise of the shoe. The abutments are carried by a horizontal bar rigidly secured to a lever fulcrumed on a vertically sliding bracket which is held raised by a tension spring.

Treadle-operated cams fulcrumed on the column engage rolls on the bracket to lower the abutments, the cams having concentric portions engagement of which with the rolls prevents upward movement with the abutments. The pad box is mounted by trunnions extending transversely of it on a vertical slide, and below this slide is another slide connected by an eccentric strap to an eccentric driven by the motor. Between the two slides is a heavy spring the initial tension of which may be varied without affecting the position of the pad box.

Between the motor and the eccentric is a clutch which is set by final movement of the treadle after the concentric portions of the cams have engaged the rolls on the bracket to impart upward movement to the pad through the initially tensioned spring. After a single rotation of the eccentric the clutch is automatically disconnected.

Downward movement of the lever with respect to the bracket is limited by an adjustable stop, and its upward movement with respect to the bracket is opposed by a light compression spring which, after the abutments have engaged the shoe, may be compressed by a movement of the cams to a position where their concentric portions engage the rolls, thus holding the abutments against upward movement. When the said compression spring is fully compressed the lever engages the sliding bracket to hold the shoe positively against upward movement. The step adjustment of the abutments is thus effected: passing vertically through blocks mounted on the horizontal bar are stems carrying the abutments.

2

Each stem is provided with a series of equally spaced holes and the block has two holes which are spaced once and a half as far apart as the holes in the stem so that a pin may be passed through either hole in the block and through one of the holes in the stem. To adjust the abutments up or down, the pin is withdrawn and entered in the other hole in the block. Then movement of the stem up or down half the distance between the holes therein will align another hole in the stem with the pin and enable it to be replaced. Thus step adjustments of the abutment equal to one-half the distance between the holes in its stem are provided. The heavy spring through which pressure is transmitted to the shoe limits that pressure to an amount predetermined by the initial adjustment of the spring.

The light compression spring between the lever carrying the abutments and the sliding bracket insures, notwithstanding the vertical step adjustments of the abutments, that enough pressure will be applied by the cams to the abutments through the compression spring to insure that the shoe will be held in position and not displaced when the pad box rises to apply pressure to the shoe.

The rate of rotation of the eccentric by the motor is such that the length of time the shoe is under pressure is very short, there being no dwell under pressure. The action of the pad upon the shoe bottom is therefore more in the nature of a blow or percussional impact. Thus the operating time on each shoe is very short and the operating rate consequently high.

These and other features of the invention will appear more fully from the following description when read in connection with the accompanying drawings and will be pointed out in the appended claims.

In the drawings,

Fig. 1 is a front elevation of the machine with the front cover plate removed;

Fig. 2 is a view, mostly in section, of the initially tensioned spring through which pressure is applied to the pad abutments;

Fig. 3 is an enlarged detail, partly in section, of the parts shown in Fig. 1;

Fig. 4 is a side elevation of the machine with the column broken away to show the driving mechanism in the base of the machine; and

Fig. 5 is an enlarged side elevation, partly in section, of the upper portion of the machine.

The illustrated machine has a hollow column 8 which comprises a number of castings assembled together. An electric motor 10 (Fig. 4) supplies power to exert pressure on the shoe bottom, a pulley 12 of the motor being connected by a belt 14 to a larger pulley 16 below it with a consequent reduction of speed. The pulley 16 is loose on a shaft 18 which is journaled in bearings 20 on a frame 22 secured by bolts 24 to the column 8. A pinion 26 attached to or integral with the pulley 16 meshes with a larger gear 28 which is loose on a shaft 30 below and parallel to the shaft 18, the shaft 30 having bearings 32 on the frame 22. Gears 26, 28 give a further speed reduction.

The gear 28 is attached to a driving member 34 of a clutch which may be of the kind disclosed in United States Letters Patent No. 448,777, granted March 24, 1891, in the name of G. W. Drake. The driving member 34 is secured to the gear 28 and includes a driven member 36 comprising an expansible band carried by the driven member, as shown in the patent above mentioned, the member 36 being secured to the shaft 30. Pivoted to the driven member 36 is a lever 38 radial movement of which outwardly from the shaft sets the clutch. The lever is so operated by a sleeve 40 mounted to slide on the shaft 30 and having a frusto-conical

end portion to engage the lever 38. The sleeve 40 is moved to the right (Fig. 4) by depression of a treadle 42 mounted on a shaft 44 at the left-hand side of the machine (Fig. 1), the shaft having bearings 45 in the frame 22 (Fig. 4). Secured to the treadle shaft 44 is an upstanding arm 46 which, when the treadle is depressed, engages a horizontal arm 48 forming part of a lever 50 fulcrumed on a vertical pin 52 in bearings 54 formed on the frame 22 a substantial distance back of the shaft 30 in Fig. 4. The end of the lever 50 carries a pin 56 engaging a circumferential groove 58 in the sleeve 40 so that depression of the treadle 42 will slide the sleeve to the right and set the clutch. Pinned to the shaft 30 is a pinion 60 which meshes with a larger gear 62 secured to the shaft 18 and to which also is secured an eccentric 64 connected by an eccentric strap 66 to a slide 68. On the shaft 18 is a cam 70 so shaped that, after about one revolution of the shaft 18, it will engage a projection 72 on the lever and swing it toward the left, the sleeve 40 then releasing the lever 38 and allowing the shaft 18 to stop.

The eccentric strap 66 (Fig. 2) is pivoted by a pin 74 to ears 76 formed on the slide 68 which is in the form of a hollow sleeve arranged to slide in a vertical cylinder 78 secured to the column 8. In the hollow sleeve 68 is an inverted cup 80 having a flange 82 resting on a shoulder 84 of the lower portion of the sleeve 68. Outside the cup and resting on the flange 82 is a long heavy spring 86 which extends up into a slide 88 which is in the form of a sleeve formed integral with a pad box support 90, the sleeve sliding vertically in the cylinder 78. A rod 92 extending centrally of the sleeve passes at its lower end through the bottom of the cup 80 and has a nut 94 threaded on its lower end and secured against rotation by a pin 96. Between the nut 94 and the bottom of the cup is a ball thrust bearing 98. Engaging the upper end of the spring 86 is a long nut 100 having a projection 102 thereon which engages a vertical slot 104 in the sleeve 88 to prevent turning of the nut. A nut 106 threaded on the upper end of the rod 92 and held from rotation by a pin 108 bears against the lower side of the pad-box support 90. The nut 100 is threaded on the long threaded portion of the rod 92 and has a square upper end 110 exposed in a hole in the pad support 90, the square end being adapted to be turned by a wrench. Turning of the rod will move the long nut 100 up or down to vary the initial tension of the spring 86 without disturbing the position of either of the sleeves 68 or 88. Hence the position of the pad-box support 90 remains the same whatever the initial tension on the spring 86. The space in the cup 80 between the nut 94 and the eccentric strap 66 permits the cup to move relatively to the nut when the spring is compressed by rotation of the eccentric.

A pad box 112, which may be of the type disclosed in my application for United States Letters Patent Serial No. 192,166, filed October 26, 1950, now Patent No. 2,602,173, granted July 8, 1952, is secured by screws 114 (Fig. 5) to a cradle 116 having trunnions 118 which are journaled in uprights 120. The uprights have reduced cylindrical portions 122 mounted in holes in the pad-box support 90 so that the cradle and pad box may be lifted off for access to the square end 110 of the rod 92. The pad box 112 and a pad 124 are constructed as disclosed in my above-mentioned patent and are effective for a variety of shapes of shoe bottoms that may be encountered in a line of work such as bottoms that are flat from heel to toe or bottoms that have a steep breast face on the heel.

To sustain a shoe on a last against upward pressure of a pad against the shoe bottom, two abutments 126, 128 (Fig. 1) are provided, one, 126, engaging the last and the other, 128, engaging the toe portion of the shoe. The toe abutment (Fig. 3) is pivoted at 130 to a square stem 132 sliding vertically in a block 134

mounted to slide on a horizontal bar 136. Vertical adjustment of the toe abutment is obtained by providing the stem 132 with a series of equally spaced transverse holes 138 (Fig. 3) to be engaged by a pin 149 which is passed through either one of two holes 142 in the block 134, which holes are so spaced that when one is in line with one of the holes 138 in the stem 132 the other is half way between two holes in the stem so that, by removing the pin 140 and moving the stem 132 up or down half the distance between the holes 138, the pin can be re-inserted in the lower hole. Thus, the two holes in the block provide twice the number of adjusted positions that can be provided by one hole in the block.

The pin 140 is retained in position by a wire spring 144 secured by a screw 146 to the block, the wire engaging a groove in the pin. The abutment 126 is provided with similar means for adjusting it vertically and each block 134 is adjustable horizontally along the bar 136 and is retained in place by a latch 148 engaging teeth 150 formed in the upper edge of the bar. The transverse bar 136 is rigidly secured at 152 to a lever 154 (Fig. 5), the rear portion of which is forked to embrace a vertically sliding bracket 156 to which it is pivoted at 158. The bracket 156 slides on a vertical shaft 160 the lower end of which is seated in a socket 162 in a housing 164 secured at 166 to the column 8 and extending up to embrace the shaft 160, a transverse shaft 168 passing through the housing and the shaft 160 to support its upper end. The bracket 156 is held raised by a tension spring 170 connected at one end to a pin 171 on the bracket and at the other to a hook 172 on the housing 164. Downward movement of the lever 154 is limited by a screw 174 threaded in the lever with its head engaging a projection 176 on the bracket 156. Upward movement of the lever is opposed by a compression spring 178 mounted in a socket in the lever and engaging a projection 180 on the bracket 156, which projection when the spring 178 is compressed positively prevents upward movement of the lever 154 with respect to the bracket 156. Upward movement of the bracket 156 is cushioned by an elastic washer 182 on the shaft 160 between the bracket and a collar 184 pinned into the shaft. On each side of the bracket 156 is a roll 186, the rolls being mounted on a pin 188 which passes through the bracket and through a vertical slot 190 in the shaft 160.

Two identical cams 192, one on each side of the bracket 156, are pivoted on the shaft 168 and engage the rolls 186. The cams are integrally connected by a web 194 which, in the normal position of the cams, engages a stop screw 196 threaded in the upper end of the housing 164. The web 194 and the two cams constitute a double cam. Each cam 192 has an inclined edge face 198 which, when the cams are moved counterclockwise (Fig. 5), moves the bracket 156 and hence the lever 154 and abutments 126, 128 downwardly, and each cam has an edge face 200 which is concentric with the pivot 168 so that in the final lowered position of the abutments they are locked positively against upward movement after the spring 178 has been compressed and the lever 154 engages the projection 180.

Operation of the cams 192 (Fig. 5) to lower the abutments 126, 128 is effected by a rod 202 connected at 204 to an arm 206 integral with the cams, the rod at its lower end (Fig. 4) being connected to an arm 208 extending from the treadle shaft 44 and secured thereto. Thus, depression of the treadle first operates the cams 192 to lower the abutments and, during the engagement of the concentric portion of the cams with the rolls 186, the arm 46 engages the arm 48 and swings the lever 50 to move the cone 40 to engage the lever 38 and set the clutch 34, whereupon, the motor 10 being of course rotating, the eccentric 64 will be turned to raise the pad through the spring 86 and press the pad against the shoe bottom and, when the eccentric shaft 18 has about com-

pleted a single revolution, the cam 70 thereon strikes the projection 72 on the lever 59 and moves the cone 40 out of engagement with the lever 38, causing the eccentric shaft to stop.

In operation, with the electric motor running, the heel and toe abutments 126, 128 are adjusted respectively to what are found to be their best positions for a shoe such as is being operated upon. The shoe with the sole spotted thereon is then placed sole downward on the pad under the heel and toe abutments and the treadle 42 depressed sufficiently to bring the abutments down on the shoe. If the shoe has not been correctly placed on the pad box, the treadle may be released to allow the abutments to be raised by the spring 170 from holding contact with the shoe whose position on the pad box may then be corrected. When the shoe is correctly placed, the operator continues to depress the treadle 42 which brings the concentric portions of the double cam 92 against the cam rolls 186, thus locking the abutments against upward movement by pressure of the shoe. The remaining treadle movement trips the clutch, causing the shaft 18 and the eccentric 64 thereon to rotate once. This single rotation of the eccentric raises the pad box 112 to press the shoe bottom with sufficient force to cause the sole assembled thereon to adhere to the shoe bottom and then lowers the pad box to its normal position corresponding to the bottom dead center of the eccentric.

The upward thrust of the eccentric 64 is transmitted to the pad box 112 through the compression spring 86. This spring serves to limit the amount of thrust of the pad box on the shoe. This is a desirable feature inasmuch as, with a fixed length of stroke of the eccentric, the adjustment of the heel and toe abutments 126, 128 may otherwise be such as to allow an undesirably high pressure by the pad box against the shoe.

The speed reductions from the motor to the eccentric, as shown, are about 4 to 1, 3 to 1, 3 to 1. Therefore, with the motor having 1200 R. P. M. the eccentric would turn about 34 R. P. M. or once in about two seconds. The time that the shoe is under pressure is therefore momentary, that is, less than two seconds, and the time of full pressure is very short and amounts to little more than an impact.

Having thus described my invention, what I claim as new and desire to secure by Letters Patent of the United States is:

1. In a cement sole attaching machine, the combination of a vertically movable pad, an abutment for a last in a shoe, an abutment for the forepart of the shoe, a bar on which the abutments are mounted, a lever rigidly secured to the bar, a manually operated cam acting to move the lever bodily with the abutments toward the shoe on the pad, and to hold the abutments positively against upward movement, a slide carrying the pad, a slide below the pad slide, a spring between the slides, power-operated means acting on the lower slide and including a non-repeating one-revolution clutch for delivering a single percussional upward impulse to the pad slide through the spring to force the sole against the shoe bottom, and means acting after operation of the cam to initiate operation of the power-operated means.

2. In a cement sole attaching machine, the combination of a frame, means for holding a shoe against upward movement, a pair of vertically movable slides mounted in the frame, a pad on one of the slides, an eccentric connected to the other slide, a spring between the slides, power-operated means for rotating the eccentric, and means for varying the initial compression of the spring without affecting the position of either slide.

3. In a cement sole attaching machine, the combination of a vertically sliding bracket, a lever pivoted to the bracket for limited movement with respect thereto, a bar secured to the lever, abutments carried by the bar, a pad on which a shoe and its sole are placed under the abut-

ments, treadle-operated cam means for lowering the bracket to cause the abutments to engage the shoe, yielding means between the lever and the bracket to permit full operation of the cam means, and means for moving the pad up to press the sole on the shoe.

4. In a cement sole attaching machine, the combination of a pad, power-operated means for raising the pad, abutments over the pad to engage a shoe thereon, a lever carrying the abutments, a vertically sliding bracket to which the lever is pivoted, a cam having a fixed pivot and two cam faces, one face being inclined and acting to lower the bracket and the other being concentric with the pivot to lock the bracket against upward movement, and a spring between the lever and the bracket to permit movement of the cam to locking position after the abutments engage the shoe, the lever after full compression of the spring engaging the bracket.

5. In a cement sole attaching machine, the combination of a frame, a vertically movable first slide mounted in the frame, a pad box mounted on the slide, abutments above a shoe placed right side up on the pad, said abutments preventing upward movement of the shoe, a second slide mounted in the frame beneath the first slide, a compression spring between the slides, a rod located in the spring and rotatably connected to the lower end of the spring, a nut on the rod engaging the upper end of the spring, means for preventing turning of the nut whereby turning of the rod will vary the initial compression of the spring, and means for giving the slide a momentary upward thrust to apply through the spring upward movement to the pad on the first slide.

6. In a cement sole attaching machine, the combination of a vertically movable pad upon which a shoe is placed right side up, abutments above the pad, a lever on which the abutments are carried, a vertically sliding bracket, a tension spring sustaining the bracket, the lever being pivoted to the bracket for limited movement with respect thereto, a compression spring between the lever and the bracket, which spring is compressed by upward movement of the lever, a stop on the bracket limiting upward movement of the lever, rolls on the bracket, a double cam engaging the rolls, a treadle connected to the double cam to lower the bracket to cause the abutments to engage the shoe and at least partially compress said compression spring, and power means operation of which is initiated by further movement of the treadle for imparting a momentary upward thrust to the pad.

7. In a cement sole attaching machine, the combination of a vertically sliding bracket, a lever pivoted to the bracket for limited movement with respect thereto, a horizontal bar secured to the lever, blocks sliding on the bar, abutments having stems extending through the blocks, said stems having equally spaced holes, said blocks having holes alineable with the holes in the stems, the holes in the blocks being spaced one and a half times the distance between the holes in the stems, pins for engaging holes in the blocks and stems, a pad on which a shoe and its sole are placed under the abutments, treadle-operated cam means for lowering the bracket to cause the abutments to engage the shoe and then hold the shoe against upward movement, yielding means between the lever and the bracket to permit full operation of the cam means, and means for moving the pad up to press the sole on the shoe.
